TOILET SEAT FOR INVALIDS

Milton Finlof, 3722 Martin Drive,
San Mateo, Calif. 94403

Filed May 19, 1975, Ser. No. 578,540

Term of patent 14 years

Int. Cl. D23—02

U.S. Cl. D23—71

Fig. 1

Fig. 3

Fig. 2

Fig. 4

Fig. 5

Fig. 6

Fig. 7

FIG. 1 is a top plan view of a toilet seat for invalids showing my new design.

FIG. 2 is a bottom plan view thereof.

FIG. 3 is a rear elevational view thereof.

FIG. 4 is a front elevational view thereof.

FIG. 5 is a side elevational view taken from the left of FIG. 3, the opposite side being a mirror image of the side shown.

FIG. 6 is a cross sectional view taken on line 6—6 of FIG. 1.

FIG. 7 is a cross sectional view taken on line 7—7 of FIG. 1.

I claim:

The ornamental design for a toilet seat for invalids, as shown and described.
